UNITED STATES PATENT OFFICE.

FRANCIS F. HEYSE AND JOHN P. TUERLINGX, OF BROOKLYN, E. D., N. Y.

WATCH-CASE OPENER.

SPECIFICATION forming part of Letters Patent No. 236,948, dated January 25, 1881.

Application filed June 21, 1880. (No model.)

To all whom it may concern:

Be it known that we, FRANCIS F. HEYSE and JOHN P. TUERLINGX, of Brooklyn, E. D., in the county of Kings and State of New York, 5 have invented an Improvement in Watch-Case Openers, of which the following is a specification.

This improvement is especially adapted to watches in which the glass is opened to give 10 access to the hands for setting the same; but the improvement is available in other cases, and may be used for opening either of the lids of the watch or for opening the bezel of the glass.

15 In all watch-cases it is important that dust be excluded from the works, and it is found in practice that this can only be accomplished by fitting the lids or bezel tightly. When this is done the case cannot be easily opened, and 20 the finger-nails are often injured in attempts to pry open the case. A knife is frequently resorted to, and the case is marred and injured by the same.

Our invention relates to the combination, 25 with the case, of a wedge-lever attached to the watch, and placed so that by moving the lever the wedge is pressed in between the parts of the case to force them apart and open the watch. By this means the case can be opened 30 with reliability, regardless of the tightness with which the parts of the case close, and the case is not injured by the action of the wedge-lever, because it is in a fixed position and not liable to slip and scratch the parts.

35 In the drawings, Figure 1 represents a watch with a portion of the face and glass removed to show the wedge-lever, and Fig. 2 is a vertical section at the line xx .

The watch-case is to be of any desired size 40 or character.

The drawings represent a watch with a

center portion, a , lid b , bezel c , glass d , and face.

The wedge-lever l is of a size suitable for the case, and it is upon a fulcrum screw or pin, h , 45 and extends to the thumb-piece i for moving the lever, and e is the wedge that projects at one side of the lever. The wedge e is to be adjacent to the joint between the lid and the body of the watch-case, or else it is to be adjacent to the bezel or ring of the watch-glass when closed.

The thumb-piece i is preferably in the form of an arc of a circle with a pin at the end, and this arc passes through a notch in the bezel or 55 rim of the case, the pin being at the outer end thereof, so that the lever is drawn upon by pulling the arc-piece and swinging the lever so that its wedge e is forced in between the parts of the case that are to be separated in 60 opening the watch.

The spring s is used to return the lever to its normal position.

It will be apparent that the lever may have the fulcrum between the wedge and the thumb-piece, and in that case the direction of motion would be varied, and under all circumstances the lever is of a size and shape to suit the place into which it is introduced in the watch-case.

We claim as our invention—

The combination, with the watch-case, of a wedge-lever adapted to be moved by the finger, and placed so that the wedge acts between two of the parts of the case to open the watch, substantially as set forth.

Signed by us this 18th day of June, A. D. 75
1880.

FRANCIS F. HEYSE.
JOHN P. TUERLINGX.
